UNITED STATES PATENT OFFICE.

ARTHUR F. POOLE, OF KENILWORTH, ILLINOIS, ASSIGNOR, BY MESNE ASSIGNMENTS, TO REMINGTON ACCOUNTING MACHINE CORPORATION, OF NEW YORK, N. Y., A CORPORATION OF NEW YORK.

CALCULATING-MACHINE.

1,394,641.

Specification of Letters Patent.

Patented Oct. 25, 1921.

Application filed September 15, 1916. Serial No. 120,233.

To all whom it may concern:

Be it known that I, ARTHUR F. POOLE, of Kenilworth, county of Cook, and State of Illinois, have invented certain new and useful Improvements in Calculating-Machines, of which the following is a specification.

My invention is an improvement in calculating machines, particularly in the type of machine first described in the patent to 10 Richmond, Number 503,986 and later in the patent to Hanson, Number 905,421, and still later and more in detail in the patent to Hart, Number 1,176,364.

The object of my invention is to improve 15 the operations of the above mentioned machines in several particulars, especially in the provision of an algebraic totalizer to such machines and in providing them with improved means for performing subtraction.

All of the above mentioned machines have carrying mechanisms which operate in the addition direction only. There is on the market a machine of the Hanson type under 20 the name of the Underwood machine which is equipped with a device for subtraction. This device works on the general principles of the cited patent to Richmond, that is, when it is desired to subtract, the connections between the numeral keys and the actuating mechanism are changed so that the 1 key determines that the numeral wheel shall be rotated eight spaces and the 2 key that said wheel shall be rotated seven spaces and 25 so on. Accordingly when a number is set up on the numeral keys, the complement of the number set up will be entered into the totalizer, said complement being obtained by subtracting each digit of the number to 30 be subtracted from nine. It is well known that the complement obtained in this manner is one unit short of the true arithmetical complement. Therefore, after the complement has been inserted an additional unit 35 is added in the units place of the totalizer, thus making the number first added the true arithmetical complement of the number to be subtracted. After these operations the totalizer will then exhibit the difference between the number in it originally and the 40 number whose complement has been added.

Throughout the following specification I shall have occasion to speak of both the number which is obtained by subtracting each

digit of said number from nine and the number which is obtained by subtracting the last significant digit of said number from ten and the remaining digits from nine. I shall speak of the former as the "complement" and the latter as the "true arithmetical complement."

Before entering into a description of the mechanism necessary to carry out my invention it will be first advantageous to give a short description of its theory of operation and subsequently describe the structure required to reduce this theory to practice. The theory being in mind, one will then more readily understand the operation of my invention.

All the algebraic totalizers of the prior art, having but a single carrying mechanism, have the following characteristics:

First, a reversible actuating mechanism; Second, a reversible carrying mechanism; 75 and

Third, some means to add a unit into the lowest numeral wheel whenever the totalizer passes through zero.

It is true that the first two of these elements are not immediately perceptible in the Burroughs type of totalizer, an example of which is that disclosed in the patent to Rinsche, Number 1,172,484. However, the two sets of totalizer wheels 916^a and 85 916^c present in the Rinsche structure serve to transform a one-way actuating mechanism into a reversible actuating mechanism, and similarly to transform a one-way carrying mechanism into a reversible carrying 90 mechanism. The two sets of totalizer wheels of the Rinsche structure, therefore, may be considered as the mechanical equivalent of a reversible carrying mechanism and a reversible actuating mechanism. 95

As before noted, there are some types of adding machines (e. g. Richmond, Underwood) having a one-way carrying mechanism in which subtraction is accomplished by setting up the complement of the subtrahend 100 and adding this complement into the totalizer. Then either during said addition or subsequently thereto adding an additional unit in the lowest place of the totalizer, and it is with this type of machine that my present invention is concerned.

To carry out my invention it is necessary to provide the numeral wheels with two sets

of numbers paired in the relation of 9-0, as usual in algebraic totalizers and to provide a shiftable shutter, the position of which is determined by the position of the highest wheel of the totalizer; that is, if the highest wheel of said totalizer stands at positive 9, this determines that the shutter will be placed to show the negative set of numbers. If said highest wheel should stand at positive 0, the shutter will show a positive set of numbers. It is to be noted, however, that the mechanism connecting said shutter and highest wheel must be such that the highest wheel is free to turn either an entire revolution or a number of revolutions without interference from the shutter. This requirement follows from the fact that in the Hanson machine the motion of the highest wheel is always in one direction. It is, therefore, necessary that said highest wheel be free to make a complete revolution or a plurality of complete revolutions without interference from the shutter. The mechanism which I use for my shutter connection consists of a cam placed on said highest wheel and a shutter having a spring tending to hold it against the surface of said cam. The high place of said cam coincides with the exhibition of the positive 9 at the reading line and serves to shift said shutter into its negative position. The number wheel may then be turned through complete revolutions without interference from the shutter which, however, will be shifted to exhibit the negative set of numbers whenever the highest numeral wheel exhibits a positive 9 at the reading line.

The actuating mechanism of the cited Underwood machine will be changed in the following particulars.

Instead of adding one in the units place of the totalizer every time the machine is operated to subtract a number this extra one is added only when the highest wheel of the totalizer passes from 9 to 0. It must be borne in mind that the highest wheel of the totalizer can be rotated in one direction only. For instance, if it is standing at 0 and the number inserted makes it stand at 9, the wheel will have to be rotated through nine spaces in the positive direction. Again, if said wheel stands at 9 and after a number is inserted stands at 0, it will be rotated but one step in a positive direction. In my herein described invention the mechanism for adding the extra one in the units place of the totalizer is operated only when the highest wheel of the totalizer has been turned through the carrying point; that is, from the 9 position to the 0 position. If the highest wheel stands at 9, and after a subtracting operation has been turned ten spaces so as to again stand at 9, a one will be added in the units place. If said wheel stands at 9 and is advanced one step to 0, a unit will

be inserted in the units place of the totalizer as a result of this operation. However, if said wheel stands at 0 and is turned nine steps so as to stand at 9, the extra unit will not be inserted, since said highest wheel has not passed through its carrying point as a result of the last mentioned operation.

Analysis will show that this plan of adding an extra one in the units place only when the highest wheel has carried will take care of all possible additions and subtractions of numbers on the Underwood machine if said machine is provided with two complementary sets of numbers and a shiftable shutter as above described.

For example, if the totalizer stood at positive 1, and two were subtracted therefrom (assuming a 3-wheel totalizer) there would be added into the totalizer 997, this being the complement of 2. Under these circumstances the highest wheel would not carry since it would be rotated from the 0 step to the 9 step. The totalizer would then read 998 on the positive numbers and 001 on the negative numbers. Inasmuch as the highest wheel of the totalizer would stand at positive 9, the shutter would be shifted to a position to exhibit the negative set of numbers, and 001 would be exhibited on the reading line. This is the correct answer to 1 minus 2.

To take another example, assume the totalizer stands at positive 010 and that twenty is subtracted therefrom. There would be added into the totalizer 979, the complement of 20, with the result that the numeral wheels would show 989 positive and 010 negative. In this case, the highest wheel of the totalizer would not carry since it would be thrown nine steps from 0 to 9, but the shutter would be shifted, and the totalizer would show negative 010, the correct answer. With the totalizer showing this reading, assume that thirty be added thereto. The wheels will then show positive 019 (989+30=019), but in this case the highest wheel will have been advanced through the step from positive 9 to positive 0 and according to the rule one will be added in the units place, changing the positive 9 therein to a positive 0, which in its turn will carry one into the tens place, changing the one therein to a two, which will leave the totalizer indicating positive 20, the correct answer of minus 10 plus 30.

In all of the above cases, it is, of course, assumed that the shutter is shifted by the highest number wheel so that when this wheel stands at positive 9, the shutter exhibits the negative digits, which may be red, and when said highest wheel stands at positive 0, the shutter exhibits positive digits, which may be colored black.

To take another example, assume that the totalizer stands at black 025, and 16 is sub-

tracted therefrom. Subtraction of the 16 will add 983 into the totalizer which will then show 998. However, the addition of the 8 to the 2 in the tens column determined 5 a carry, and this carry will add a unit in the hundreds place. This unit added to the nine previously introduced by the actuating mechanism will again cause a carry and one will be added in the units place of the totalizer. The addition of this one will change the 8 in said units place to a 9, and no further carrying will take place. The totalizer will now show in black 009, the correct answer of 025 minus 16.

10 In carrying out my invention it is further necessary to provide a trip for the actuating mechanism which is controlled from the highest wheel of the totalizer. In the particular embodiment in which I have shown my 15 invention an electric motor serves to furnish the power to operate the machine. This motor is tripped by hand after a number has been set up. Under some circumstances arising in my hereafter described machine it is 20 necessary that this motor, after having once been tripped by hand, be again tripped so as to go through an additional cycle. One of the objects of my invention is the means 25 for this repeated and automatic tripping of 30 said motor.

I have also shown herein an alternative construction in which a certain portion of the carrying mechanism always goes through two cycles, and in this particular form the 35 repeated tripping of the motor is rendered unnecessary. I shall explain both forms of my invention hereinafter.

Having thus, in a general way, described the theory on which my invention is constructed I will now give a description of the mechanism necessary to reduce this theory to practice. This mechanism may be best understood by reference to the accompanying drawings, in which—

45 Figure 1 is a side elevation partly in section along line 1—1 of Fig. 2.

Fig. 2 is a plan view of some of the parts of the computing mechanism contained in the base underneath the typewriter shown in 50 Fig. 1.

Fig. 18 shows a modification of the carrying mechanism operator designed to dispense with the repeated action of the motor.

Fig. 19 shows another modification of the carrying mechanism designed to dispense 90 with a repeated cycle of the motor.

Throughout these drawings similar reference numbers apply to like parts.

My invention above noted is shown applied to typewriter computing machines of 95 the general type of a ten key computing machine, in which there are ten keys, any one of which may operate in any decimal place of the number set up by said keys and the decimal place of operation of the key is 100 determined by a decimal carriage, moving step by step as the keys are depressed one after another and thus determining the key set-up of the actuating mechanism in a particular decimal place. After this set-up has 105 been made; that is, after the digits of a number have been set up by the keys then a general operator is put into action and moves a set of register bars to an extent determined by the key set-up. In mesh 110 with each of said register bars is a gear wheel which is connected by a slip ratchet engagement to a number wheel of a totalizer. The front stroke of the general operator moves the ratchet bars forward an extent 115 determined by the set-up and rolls the number determined by said set-up into the totalizer numeral wheels. On the back stroke of the general operator the ratchets connecting the numeral wheels to the gears engaged by 120 the register bar slip backward and also on this back stroke a carrying mechanism connecting the numeral wheels in the totalizer comes into action and performs the carrying resulting from the particular number just 125 added into the totalizer.

The key set-up.

Referring particularly to Fig. 1, 20 is a typewriter having a set of numeral keys 21, 130

- each of which is connected to a type bar 22 which serves to print the number associated with said key on a platen 23. The platen is drawn to the left by a spring (not shown) and its motion is controlled by an escape-
ment mechanism 24 which allows a type-
writer carriage 27, on which is mounted said platen, to escape step by step on the actuation of the numeral keys 21.
- Attached to the framework 30 are a plurality of triggers 25 which are pivoted on the framework 30 on a rod 26, these triggers being spaced apart according to the particular spacing in which it is desired to write the numbers on the machine. Attached to and moving with the typewriter carriage 27 is a decimal selector 28 which, during the travel of the carriage, contacts with the triggers 25 and elevates the left hand ends thereof one after another. A rod 29 extending under the triggers 25 serves to hold them in a normal position where they are adapted to be raised by the decimal selector 28 as said selector moves during the travel of the typewriter carriage. Coöperating with each of the triggers 25 is a push rod 31, the lower end of which is engaged by a rocker 32 pivoted on a rod 33 mounted in the framework 30. There is one of these rockers for every push rod 31 and consequently for every trigger 25. Referring particularly to Fig. 6, and the top portion of Fig. 4, each of the rockers 32 serves to operate a transposing bar 34, each of said bars being supported on the ends of bell cranks 35 and 36 rotatably supported on rods 37 and 38 in the framework 30. Said bell cranks 35 and 36 have depending lower ends which are connected by a link 39, the object being to form a species of parallelogram linkage and thus to constrain the transposing bars 34 to move in an approximately vertical direction when any of said bars is moved by motion of its associated rocker 32.
- The necessity for this transposing bar arises from the fact that due to the motion of the typewriter carriage to the left during the insertion of a number the decimal selector 28 encounters right hand trigger 25 first and this trigger controls the left hand decimal section of the actuating mechanism. It is, therefore, necessary to transpose the action of the triggers 25 so as to get the digits of a number arranged in their proper order in the actuating mechanism.
- Each one of the transposing bars 34 has on it a lug 40 which contacts with a bell crank 41 mounted on a series of rods 42 and each of said bell cranks contacts with the pin 43 in its associated register bar 44. It will be noted from Fig. 3 that each of the rockers 32 is of a shape to engage with but one of said transposing bars 34. It will be also noted from the same figure that the ends of said rockers carrying push bars 31
- are of different lengths to compensate for the varying lengths of the front portion of said rockers 32, the object being to give each of the transposing bars 34 uniform vertical motion upon the actuation of the triggers 25 connected to said bar 34 by the decimal selector 28.
- The register bars 44 (Figs. 1, 2, 3 and 11) are mounted in the framework so as to be able to move longitudinally. Each register bar has on its forward end a series of rack teeth 45 which engage a pinion 46 which, through a slip ratchet device, drives a totalizer number wheel 50. Mounted on the intermediate portion of each of said register bars 44 is a series of denominational pins 47 which are mounted in said register bar so as to be movable at right angles thereto. Said denominational pins are provided with snappers (not shown) so as to hold them in their alternate positions, there being one position of the denominational pins 47 which corresponds to said pin not having been actuated by the set up mechanism hereinafter to be described and a depressed position of said denominational pin 47 corresponding to said pin having been actuated. The register bars 44 are held in their normal position shown in Fig. 3 by a series of spring actuated arms 51. Said arms are mounted in a series of annular grooves cut in a bar 52 mounted in the framework, and springs 53 serve to hold the lower ends of said arms 51 in contact with recesses 54 in the register bars 44, thereby holding said register bars 100 in contact with a portion of the framework 30 and thus defining a normal position for said bars and the chain of levers connecting any bar to its trigger 25. Extending over the entire series of denominational pins 47 is a set of unit bars 55. Each of said bars is connected by mechanism hereinafter to be described to one of the typewriter numeral keys and is adapted to be depressed when said numeral key is operated. Reference to Fig. 3 will show that the normal position of the denominational pins 47 is intermediate between the two adjacent unit bars 55; therefore, in case any of said bars 55 is depressed when the register bar is in its normal position the associated denominational pins will not be actuated. Progress of the typewriter carriage and contact of the decimal selector 28 with a trigger 25 will result in shifting one of the bars 44 to a position where the denominational pins 47 will be under the unit bars 55. Since the decimal selector 28 contacts with but one trigger 25 at any position of the typewriter carriage, it is obvious that but one of the register 125 bars will be displaced at a time, and as the typewriter carriage progresses toward the left that the register bars beginning at the one on the extreme left, the highest denominational place, will be successively brought 130

The general operator.

into a position to bring the denominational pins 47 mounted thereon in a position to be actuated by the unit bars 55. Consequent depression of one of the said unit bars will 5 shift a denominational pin 47 in but one of said bars into its alternate position, in which position it is subsequently engaged by a general operator hereinafter to be described.

Having now described the means by which 10 the register bars 44 are successively brought into position to have their denominational pins 47 actuated by the unit bars 55, I will now describe the mechanism connecting said unit bars with the typewriter numeral keys 15 21. Attached to the lower portion of each one of said numeral keys 21 is a depending link 56, a portion of which is adapted to co-operate with a single key mechanism (not shown), the object of said mechanism being 20 to prevent the depression of more than one of said numeral keys 21 at a time. The depending links 56 are guided in the framework so as to have an approximately vertical motion and their lower ends are adapted to 25 contact with and actuate a series of rocker arms 57, each of which is attached to a rock shaft 58 rotatably mounted on the framework 30 of the machine. The rock shafts 58 have also a longitudinal movement in respect 30 to the framework 30, this movement being for the purpose of throwing the machine into subtraction in a manner hereinafter to be described. Mounted on each of the rock shafts 58 are two arms 59 and 60, which are 35 adapted to engage pins 61 and 62 mounted in a series of tie bars 63, each of which is mounted on bell cranks 64 and 65 rotatably mounted on rods 66 and 67 in the framework 30. On the horizontal arm of said bell 40 cranks is pivoted the unit bar 55. From the chain of mechanism thus described it will be seen that a depression of the typewriter numeral keys will result in a depression of one of the unit bars 55. All the unit bars are 45 held elevated in a normal position by a series of springs 68 extending between the tie bars 63 and the framework 30. Reference to Fig. 2 will show the fifth rock shaft 58 is provided with but one arm 59, since 50 said arm is adapted to engage either a pin in the fifth tie bar or a pin in the fourth tie bar, the complement of five being four. Similarly the ninth rock shaft 58 has but one arm 59, since said arm is adapted to 55 engage either the pin of the ninth tie bar or engage no pin at all, the complement of nine being zero.

From what has gone before it is apparent that any number which is set up by the typewriter numeral keys 21 and written on the platen will be reproduced in a displacement of the denominational pins 47, leaving these pins in a depressed position ready to be picked up by the general operator when the 60 same shall be brought into operation.

The function of the parts of the machine described under the general heading of the general operator is at the proper time to enter the number set up on the register bars 44 into the totalizer, and subsequent to said entry to actuate the carrying mechanism of the totalizer and return the bars and denominational pins to their normal position. In 70 my improved machine I have shown the motive power or prime mover of the general operator to be an electric motor normally at rest. After the number has been set up the circuit of the motor is closed by means hereinafter to be described, and certain mechanisms are brought into operation and are moved through a complete cycle by the rotation of the motor. Upon the completion of a cycle the motor is disconnected and allowed to come to rest by its own friction and simultaneously with the disconnection of the motor, its circuit is broken so as to cut off its electric power. Under certain circumstances hereinafter to be described it is necessary that the general operator go through 80 two cycles. Accordingly mechanism is shown for automatically tripping the motor 85 a second time under these circumstances.

I shall first describe the mechanism by 90 which the motor is thrown into action and drives the general operator. Referring particularly to Figs. 1, 3, 7, 8, 9 and 10, electric motor 70 is secured to the framework which serves to support the machine. This motor 100 is preferably a series motor so that it will have a strong field and pick up its speed very rapidly. In other words, it is desirable that this motor have a large starting torque. The current is taken from the main 72 by a conductor 73 which is connected to a contact spring 74 grounded on the frame of the machine. Current from the other main 71 is brought through the field of the motor 75 to the motor armature and thence to a contact spring 76 insulated from the framework of the machine. It is to be noted that all the windings of the motor and the brushes thereof are insulated from the machine frame, and it is further to be noted 110 that in case it is desired to keep all current out of the machine itself the contact spring 74 may also be insulated from the framework. Closing of the contact springs 74 and 76 will, therefore, give current to the motor 115 70 and the motor will start to rotate. The shaft 77 of the motor has mounted on it a disk 78 in which is a slot and in this slot is a pin 79 on the end of a crank arm 80 which is on a worm shaft 81 rotatably mounted in 120 the framework and carrying a worm 82. Connection of the pin 79 and the slot of the disk 78 is for the purpose of avoiding the necessity of an exact alinement between the shaft 81 and the shaft 77. The worm 82 130

meshes into a worm wheel 83 loose on a shaft 84 which also turns in the framework. Rigid with the shaft 84 is a disk 85 on which are mounted two pawls 86 and 87 which are given a tendency to turn about their pivots 88 and 89 by tension springs 90 and 91. The springs 90 and 91 tend to bring pawls 86 and 87 into engagement with a ratchet wheel 92 which is rigid to the worm wheel 83, and like 10 said wheel turns loosely upon the shaft 84. The pawls 86 and 87 are prevented from coming into contact with the ratchet wheel 92 by a pair of pins 93 and 94 which are mounted on a plate 95 which also rotates on 15 shaft 84 and the extent of said rotation relative to the disk 85 is determined by the extent of the oblong slots 96 and 97 in the disk 85. Said plate 95 is held adjacent to disk 85 by two screw studs 219 and 220, Fig. 3, 20 and has projecting at right angles to its plane an ear 98, and this ear is connected by a tension spring 99 to a post 100 on the disk 85. Mounted on the plate 95 is a contact spring operating member 101 which is insulated from said plate and contacts with a hump 102 in the contact spring 74. When the parts are in the position shown in Figs. 8 and 10 it will be seen that the circuit is open. Tendency of the ear 98 to rotate in 25 the direction in which it is urged by the spring 99 is prevented by the lower end 103 of a trip plunger 104. The operation of the motor starting mechanism is as follows:

The plunger 104 is raised by means hereinafter to be described whenever it is desired to have the general operator go through a cycle. The withdrawing of the end 103 of 30 said plunger from the path of the ear 98 results in the tension spring 99 rotating the plate 95 relative to the framework, and also the disk 85 which at that time is stationary. This rotation results in, first, the engagement 35 of the pawls 86 and 87 with the ratchet wheel 92; second, in the contact of the spring 74 with the spring 76, thereby closing the circuit 40 through the motor 70 and starting the same. The motor then starts to revolve, driving the worm wheel 83 and the ratchet wheel 92 rigid therewith, and since the pawls 45 86 and 87 are at this time in contact with said ratchet wheel the disk 85 on which said pawls are mounted is turned, and with the disk the shaft 84 on which said disk is rigidly mounted. Before the disk 85 has 50 turned through a complete revolution the trip plunger 104 is restored to its normal position by means presently to be described; therefore, the ear 98 encounters the end 103 when the parts have turned through a complete 55 revolution. This contact will arrest the plate 95 and also hold the contact springs 74 and 76 separated from each other, these springs having been separated when the contact spring 101 encountered the hump 60 102 on the spring 74. The momentum of

the moving parts will continue to rotate the disk 85 until the pawls 86 and 87 by their contact with their associated pins 93 and 94 will be disengaged from the ratchet wheels 92. Since as will hereinafter be described, the tension of the spring 99 is not sufficient to rotate the disk 85 in a clockwise direction the parts will remain in the position shown in Fig. 8 until the next time the trip plunger 104 is actuated. It will 70 be observed that as soon as the pawls 86 and 87 are disconnected from the ratchet wheel 92 that the motor is free to rotate, idly turning the worm gear 82 until friction brings the motor to rest. The mechanism just described results in the shaft 84 being turned through one complete revolution every time the trip plunger 104 is actuated.

I shall now describe the mechanism by 85 which this single revolution of the shaft 84 is transformed into a forward and back motion of a certain transverse bar 105, which serves to pick up the various register bars 44 and move them an amount determined 90 by the particular denominational pin 47 which has been set up in each bar. Slidably mounted in the framework is a reciprocating pitman 106 (shown in dotted lines in Fig. 1) having bearing bars 107 and 108 95 and also having a vertical slot 109 therein. Engaging the vertical slot 109 is a pin 110 mounted on the end of a crank 111, which is rigid with the shaft 84. This arrangement will give a well known simple harmonic motion to the pitman 106 on one revolution of the shaft 84. The pitman will be gradually accelerated from a position of rest, then brought to a position of rest at the extreme limit of its travel, then accelerated 100 on its return and subsequently retarded until it comes to rest in the position shown in Fig. 1; it then has made a complete forward and back reciprocation. Mounted on and traveling with the pitman 106 is an ear 112 105 110 which engages a slot 113 in a slide beam 114 which is slidably mounted in the framework.

The front portion of the slide beam 114 has thereon a set of rack teeth 115 which 115 engage a gear 116 rotatably mounted on the framework, said gear engaging in a gear segment 215 which is mounted on a shaft 216 turning in the framework and extending clear across the machine. On 120 the other end of said shaft 216 is a sector similar to 215 which engages a gear similar to the gear 116 which, in its turn, engages teeth similar to the teeth 115 on a slide beam 193. I have not shown the sector 125 and gears co-operating with the slide beam 193, since they are not only shown in the said patent to Hart but are simply a duplication of the gears 116 and the sector 215. The object of the above mentioned gear train 130

is to give the slide beam 193 motion synchronous with the slide beam 114. The transverse bar 105 has its end supported in these two beams, and, therefore, moves 5 synchronously with them. One revolution of the shaft 84, will, therefore, result in a to and fro motion of the transverse bar 105. On its forward stroke this bar will move freely until it encounters a denominational 10 pin 47 which has been depressed by any of the unit bars 55. As this transverse bar 105 moves forward it will continue to pick up these pins and until it has picked up by means of these pins all of the register 15 bars 44 in which a pin has been displaced. The numbers set up on said bars will, therefore, be rolled into the totalizer on the forward stroke of the transverse bar 105, and on its backward stroke the transverse bar 20 will encounter shoulders 118 present on the register bars 44, and by means of these shoulders will return said racks approximately to their normal position.

When the transverse bar 105 starts to 25 move the register bars 44 the arms 51 will be pushed out of the recesses 54 and ride on the tops of the rear ends of the register bars 44. However, when said register bars are returned by the rearward motion of the 30 transverse bar 105 these slots will again be engaged by the arms 51 and the register bars returned to the normal position, as shown in Fig. 3. In this figure it will be noted that there is some little space between 35 the shoulders 118, by which the register bars 44 are returned by the transverse bar 105, and said transverse bar, this space being to allow the displacement of the register bars 44 during the setting up of the number.

40 I will now describe the means for operating the trip plunger 104 to trip the motor to move the general operator through a single cycle. The plunger 104 has in its upper portion a slot 173 engaging in which 45 is the end 174 of a lever 175 pivoted on the framework at 176 and urged downward by a spring 177. A motor bar 178 is pivoted to the framework of the machine at its rear end at 179 and on the forward end of this 50 bar is mounted a lug 180 which serves as a support for a handle 181 which operates the means for tripping the plunger 104. Obviously pressure on the handle 181 will depress the motor bar 178 and thereby depress 55 the lever 175 and elevate the plunger 104, thus tripping the motor. The machine will then run through a single cycle.

On the return of the transverse bar 105 60 the totalizer carrying mechanism is operated in the manner hereinafter to be described, and it is also necessary after said bar has nearly reached its normal position to reset all of the denominational pins 47 in order to have the actuating mechanism ready to 65 receive the next number set up by the keys.

For this latter purpose there is a restorer plate 201 which is supported by means of depending lugs 202 and 203 on bell cranks 204 and 205 which are connected at their lower ends by a link 206. The bell cranks 70 204 and 205 are rotatably supported on rods 207 and 208 which are supported in the framework. The object of the link 206 connecting the bell cranks is to give the same parallel motion. On the side of the slide 75 beam 114 is mounted a pawl 209 pivoted at 210 and held against a stop by a spring 211. Said pawl is adapted to engage an arm 212 mounted on the shaft 207. When the slide beam 114 travels forward during the setting 80 up of a number the pawl 209 snaps under arm 212 and produces no effect on said arm. On the return stroke of the beam 114 said pawl encounters the lower side of said arm and tilts it in passing. Rigid on the shaft 85 207 is an arm 213 which bears against the underside of the restoring plate 201; consequently when the arm 212 is tilted by the pawl 209 the restorer plate 201 is elevated and will restore all of the pins which have 90 been set for the number just accumulated. The mechanism is then, as far as the pins are concerned, ready for a new number, and the plate 201 is restored to its normal position by gravity. 95

The totalizer and carrying mechanism.

The totalizer consists of a series of numeral wheels 50 rotatably mounted on a shaft 48 which wheels I have by a series of slip 100 ratchets, shown in dotted line in Fig. 11, connected to the gear wheels 46, these gear wheels, as heretofore noted, being engaged by the register bars 44. Forward motion of said register bars is thus translated into 105 a turning of the totalizer wheels 50 in a clockwise direction (Fig. 11), the backward motion of said wheels being prevented by latches or dogs 119 rotatably mounted on a rod 120 supported in the framework and 110 each held in engagement with a gear 121 by a spring 122. The other end of said spring 122 is connected to an aliner 123, whose function will presently be described. The gears 121 are rigid with the totalizer 115 numeral wheels 50. Each of the wheels 50 has a carrying tooth 124 which serves, by its engagement with a gear 125 mounted on a shaft 126, to displace said gear so that a tooth 127 is thrown into the path of a tooth 120 128 on a disk 129 rigidly mounted on a shaft 130. Subsequent to the action of the numeral wheels 50 the shaft 130 is given a complete revolution, as will be hereinafter described, and during said revolution if any 125 of the carrying pieces, comprising the gear 125 and its associated parts, has been displaced, the teeth 128 will rotate said carrying piece the extent of 120 degrees by means of the teeth 127. This will bring a carry- 130

ing tooth 131 rigidly mounted with the gear 125 into engagement with the gear 121 on the totalizer wheel 50 of next higher order. Said wheel will, therefore, be advanced one 5 step and the accumulated ten of the wheel of lower order will be properly transferred. There is a set of the parts shown in Fig. 2 to each decimal order of the totalizer, the various disks 129 being placed on the shaft 130 in spiral arrangement so that the carrying done by said disks begins with the totalizer wheel of lowest order and progresses to the wheel of the highest order. In some 10 circumstances it is necessary to carry twice 15 for one actuation of the totalizer wheels; that is, it is necessary to turn the shaft through two revolutions instead of one. However, this action will be described hereinafter. The carrying piece 125 is held in 20 a normal position by the aliner 123 engaging a star wheel 117 which is rigid both to the gear 131 and to the gear 125.

I will now describe the means by which, on the return movement of the slide beam 25 114 the shaft 130 is turned through a complete revolution. Connected to the rack teeth 115 is a gear 172 which is rotatably mounted on the framework and corresponds with the function of gear a^{17} of Fig. 14 of 30 said patent to Hart, Number 1,190,171. The gear 172 meshes with a gear (not shown) on the shaft 130, which shaft and gear corresponds to the shaft a^{14} and the gear a^{16} in the said patent to Hart. The gear on the 35 shaft 130 is connected to said shaft by a one-way clutch similar to that described in the said patent to Hart. The function of said clutch is to suppress the forward motion of the slide beam 114 and to render 40 the backward motion of said slide beam alone effective in rotating said shaft 130. The gear connections between the slide beam 114 and the shaft 130 are such that the backward motion of said slide beam causes the 45 shaft 130 to turn through a complete revolution and no more.

The action of this carrying mechanism is similar to that of patents to Hanson and Hart. The gear 125 is first displaced 50 through a part of its angle by the action of the carrying tooth 124. Subsequent rotation of the shaft 130 turns it through the remainder of its angle and carries the tooth 131 through the wheel of the next higher 55 order. It is to be noted in Figs. 13 and 14 that on the surface of the number wheels 50 are two sets of numbers paired in the relation of 9-0. The function of these numbers will be referred to hereinafter.

60 *Means to throw the machine into subtraction.*

I shall now describe the means by which this machine is thrown to operate in subtraction instead of into addition. Owing 65

to the fact that this machine subtracts by means of complementary addition, there are quite a number of actions which are necessary to prepare the machine to perform subtraction. It will be recalled that when the 70 machine is thrown into complementary addition the connections of the numeral keys are changed; that is, the one key no longer operates the 1 unit bar 55 but operates the 8 unit bar 55; similarly the two key is disconnected from the 2 unit bar 55 and operates the 7 unit bar 55. The 9 key is disconnected from the 9 unit bar while the machine is in subtraction and does not operate any unit bar whatever during that 75 time, since the complement of nine is zero. On account of this disconnecting of the 9 key it is necessary to artificially depress the 9 denominational pins of all of the register bars 44 for the purpose of inserting 9 in 80 any denominational place which is represented by zero in the printed number. However, in case a number is set up on any register bar 44 it is necessary to get rid of the 9 set up previously made on that particular bar and replace said 9 set up by the 85 complement of the particular digit corresponding to the operated number key. Owing to the fact that the machine may not be put into subtraction until after the 90 typewriter carriage has been tabulated to the decimal place of the first figure it is necessary to add another function to this already complicated mechanism and this is, at the time the subtraction key is depressed 100 95 to set up the nine pin not only of all register bars 44 which remain in their normal position but of any register bar which may have been displaced from its normal position by reason of contact of the decimal selector 28 with a trigger 25.

I will first describe the mechanism which shifts the rock shafts 58. The subtraction key 132, shown in perspective in Fig. 17, is on the end of a link 133 which is connected to an arm 134 rigid to a shaft 137 and held by a spring 135 in a normal position by the contact of a pawl 136 rigid on the shaft 137 with a notch in the subtraction bar 138 which reciprocates in the 110 framework. Pawl 136 serves to hold the subtraction bar 138 in a position against the tension of a spring 139 extending between an ear 140 on said bar and a stud 141 in the framework 30. Upon the release of the subtraction bar 138 by motion of the pawl 136 a number of actions occur, which actions 115 it will be most advantageous to consider separately. First, a stud 142 is withdrawn from the path of an arm 143 rigidly mounted on a shaft 144, which turns in the framework and which is urged to turn in the direction of the arrow by a coiled spring 145. Rigidly mounted on said shaft is an arm 146, against which is constrained a pin 147 120 125 130

by a jaw 148 rotatably mounted on the shaft 144 and held against said pin by a tension spring 149. The pin 147 is mounted on an arm 150 secured to a universal bar 151, one end of which is pivoted in the framework at 152 and the lower edge of said bar engages slots 153 in all of the shafts 58. Obviously the position of said rock shafts is determined by the position of the universal bar 151 and from this it follows that when the shaft 144 is rotated that all the rock shafts 58 will be moved toward the front of the machine. This action will disengage the set of arms 59 from their coöperating pins and engage the subtraction set of arms 60 with their pins. The relation of the numeral keys to the unit bars will thus be changed, and the complement of the number set up on the number keys will be set up 20 on the denominational pins 47.

Having described the method by which connection of the numeral keys is shifted, I will now describe the mechanism which sets up the 9 denominational pins 47 in all the 25 register bars. Directly above said 9 pins, when the register bars 44 are in their normal position is a bail 154 rigidly mounted on a shaft 155 rotatably mounted in the framework and having rigid on the right hand 30 end thereof a latch 156 which is urged by a spring 157 extending between said latch and a stud 158 in the framework to turn in a clockwise direction. The normal position of said latch 156 is defined by the stud 159 35 mounted in the framework. When the subtraction bar 138 is pulled toward the rear by the spring 139 a detent 160, pivoted at 161 on the subtraction bar 138 and having an upwardly extending portion 162 adapted 40 to ultimately contact with a stop pin 163 fastened to the framework, will rotate said latch 156 in a counter clockwise direction and thereby depressing the bail 154 setting up the 9 denominational pins 47 in all of the 45 register bars which are at that time in their normal position. Continued motion of the subtraction bar 138 toward the rear will cause the upwardly extending portion 162 of the latch 160 to contact with the pin 163 50 and said latch will be disengaged from the latch 156 which thereupon, under the influence of spring 157, will return to its normal position. The above motion will be sufficient to depress the 9 denominational 55 pins of all the register bars 44 which are in their normal position. It is, however, necessary to take care of any register bar which is then displaced from its normal position by the action of the decimal selector 28. 60 This is accomplished in the following manner:

Pivoted on each register bar 44 is a lever 164, the front end 166 of which engages a cut portion in the 9 denominational pin 47 65 and is pivoted on the register bar 44 at 165.

Just back of its front end 166 this lever 164 has a part in a position to be engaged by the bail 154 in case the bar 44 has been moved forward by the denomination selecting mechanism. Obviously the 9 pin may then 70 be depressed either by contact with the bail 154 or by contact of said bail with said portion of the lever 164. Obviously all the nine pins will then be displaced upon the operation of the bail 154 irrespective of 75 whether one of the register bars 44 is in a displaced position.

I will now describe the mechanism by which the 9 pin which has been depressed in any of the register bars is restored to its 80 normal position in case any other denominational pin 47 is set up on said bar. Each one of the rock shafts 58 has on its rear end an arm 167, which arm is adapted to engage a pin 168 in a tie bar 169 whenever said rock 85 shafts are thrown into their subtracting position. Connected to the said tie bar 169 is a universal bar 170 which operates in a manner similar to the unit bars 55; that is, whenever the tie bar 169 is rocked by any 90 of the arms 167 said universal bar 170 is depressed. The lever 164 has a rearwardly extending portion 171, and said portion is directly under the universal bar 170 when the register bar is thrown forward by action 95 of the decimal selector 28. Consequently the universal bar 170 is depressed every time any numeral key is operated when the machine is in subtraction, and such depression will, therefore, serve to restore the lever 164 100 to its normal position and thereby restore the then displaced 9 pin to its normal position. On the under side of the subtraction bar 138 is a nose 214 which is engaged by the transverse bar 105 when 105 said bar is at the end of its front stroke and said bar 138 is thereby restored to its normal position and the parts operated by said bar return to their normal position also. It is to be understood that the subtraction key 110 132 is not held depressed during the operation of the machine.

The algebraic mechanism.

The mechanism peculiar to my algebraic 115 totalizer is best shown in perspective in Fig. 15, inspection of which will disclose that the shaft 126, which it will be remembered is rotatably mounted in the framework, has rigid on its left end a carrying gear 182 120 which is similar to the gears 125 loosely mounted on said shaft and hereinbefore referred to. Also rigidly attached to the shaft is a carrying gear structure consisting of a three-toothed gear 217, an aliner gear 125 218 and a gear 183 to be actuated by the disk 129 which is the lowest one of the series of carrying disks. The three-toothed gear 217 operates in the totalizer gear 121 attached to the wheel 50 in the units order; conse- 130

quently when the highest wheel of the totalizer carries, an additional unit is carried into the lowest denomination of the totalizer. Rigid on the shaft 126 is a three-pronged spider 184 whose function is to trip the plunger 104 whenever the highest wheel carries. This function is accomplished by an arm of the spider contacting with a lever 185 pivoted on the framework at 186 and having a latch 187 on the lower end thereof serving to maintain a pin 188 on a lever 189 in the position shown in Fig. 15. Said lever 189 is pivoted on the framework at 190 and is urged by a spring 191 to rotate in a clockwise direction, and its rear end extends over the lever 175. Said spring 191 is of sufficient strength to overcome the spring 177.

The spider 184 is so related to the highest wheel of the totalizer that when said highest wheel carries the arm of the spider contacts with the lever 185 and is pushed beyond its said lever, thereby tripping said lever in its motion. This will at once insure a second cycle of the general operator, during which 25 cycle the spider 184 will be carried through the remainder of its angle of motion. A spring 192 serves to hold the lever 185 in contact with the pin 188. In case the shaft 126 is rotated it is obvious that an arm of the spider will trip the plunger bar 104 and the general operator will go through an additional cycle. This additional cycle is necessary to take care of any carrying in the lower orders of the totalizer, resulting from carrying in the highest wheel, for instance, the addition of 2000 to 1000. In this case after the first carrying there will be a second carry from the units wheel up through the thousands wheel, and in order to accomplish 35 this extra carry it is necessary that the shaft 130 make a second revolution.

The slide beam 193, as previously described, moves synchronously with the slide beam 114, and on this slide beam 193 is a hump 194 which is adapted to contact with a hump 195 on the lever 189 and reset said lever after the operation of the spider 184 has caused the general operator to go through a second cycle.

Mounted on the framework of the machine is a shutter 196 which is adapted to slide the distance of the slots 197 and expose either one or the other of the two sets of numbers on the number wheels 50. A spring 198 serves to hold this shutter in the position shown in Fig. 13 and the highest number wheel 50 has a projection 199 thereon which acts on a cam 200 rigidly mounted on to said shutter. When the highest number wheel is in the position in which the positive zero is opposite the reading line the shutter is in the position shown in Fig. 13. When the highest number wheel is in the position in which the negative zero is opposite the reading line the shutter is in the position

shown in Fig. 14. The ten numbers on the number wheels may be colored in different colors, for instance, the positive numbers may be colored black and the negative numbers colored red; thus affording an easy 70 method of distinguishing whether the machine denotes a positive total or a negative one.

Considering the numbers exhibited by the totalizer and the numbers entered into the 75 machine there are six possible classes of operation. These six classes are listed in the table below.

Class.	Number in totalizer.	Number entered.	
1	+	100	10 1 cycle
2	+	100	200 1 cycle
3	+	100	90 2 cycles
4	-	100	200 1 cycle
5	-	100	90 1 cycle
6	-	100	200 2 cycles

Classes 1, 2 and 3 are when to a positive number in the machine a positive number is added; a greater number is subtracted or a less number is subtracted. Classes 4, 5, and 6 are those in which, with a negative number initially in the machine, a number is subtracted, a number less than the totalizer reading is added, or a number greater than the totalizer reading is added. In the third column of the table is set forth the number of cycles to be gone through by the carrying mechanism in each of these six cases.

It will be observed that every case is under the rule to add a unit in the lowest order of the totalizer whenever the highest wheel of the totalizer passes from nine to zero. Sometimes this requires but one cycle of the carrying mechanism, e. g. case 4 in which the highest wheel of the totalizer is turned 105 through zero as a result of an actuating operation. In this case, the latch 185 is tripped early in the forward stroke of the operating bars 114 and 193, and lever 189 is restored by hump 194 during the first cycle. The extra one is added on the units wheel in the first part of the return stroke of bars 114, 193. Whenever the highest wheel is turned through zero as a result of a carrying operation, the carrying mechanism has to go 115 through two cycles: e. g. case 3. In this case, the latch 185 is tripped in the last part of the return stroke of bars 114 and 193, and too late in the operation for hump 194 to restore lever 189 during the first cycle of operation.

A modification of my invention which dispenses with the use of the additional trip for the plunger 104 and the consequent second cycle of the general operator is shown in Fig. 18. In this figure the gear connection between the slide beam 114 and the rock shaft 130 is such that said shaft makes two revolutions in the backward motion of said slide beam 114 instead of one revolution. This will take care of the carrying in all 120 125 130

cases and will avoid the necessity of running the general operator through two cycles every time the highest wheel of the totalizer carries, I prefer the modification shown in 5 Fig. 18 in practice since it avoids the second cycle of the general operator and consequent loss of time. However, I have shown and described both forms in this specification.

It will be obvious that instead of turning 10 the shaft 130 through two revolutions, as just described, an equivalent result can be secured by arranging the cams 129 so that each cam will carry twice on each revolution of the shaft 130; that is, each cam will 15 have two teeth on it and these teeth will be so arranged that a carry will take place from the lowest to the highest order and immediately after the highest wheel has carried a carry takes place in the lowest 20 wheel and progresses a second time to the highest wheel. In other words, the essential requirement for any of the plans of tripping the motor twice, revolving the shaft 130 through two revolutions or revolving said 25 shaft through but one revolution and having two teeth on each of the cams 129, is that there shall be two cycles of carrying from the lowest wheel of the totalizer to the highest. 30 In Fig. 19 I have shown the modification just described. Reference to said figure will disclose that each of the cams 129 has two sets of carrying teeth on its circumference and for this reason will carry twice during 35 a single revolution of the shaft 130 in case a second carry should be determined by the fact of the gear 217 being displaced. In the event that the arrangement of two sets of carrying teeth on the cams 129 is used, it is 40 evident that the spider 184 (Fig. 15) will be omitted, since the second cycle of the motor will not be necessary. It is, of course, necessary that the carrying teeth on the cams 129 be arranged in a spiral, and since there 45 are two sets, there will be two spirals on the shaft 130, each spiral occupying somewhat less than 180°. The spirals are so arranged that the carrying will progress from lowest to highest. I have made but a diagrammatic 50 showing in Fig. 19, since this double spiral arrangement will be obvious to those skilled in the art.

Many changes and variations may be made in the herein described device without departing from my invention, since what I claim as new is:

1. In a calculating machine, the combination of a set of totalizer wheels, a shaft having teeth mounted thereon, said teeth being 55 adapted to actuate said totalizer wheels successively to carry said elements, a source of power, means to connect intermittently said source of power to said shaft, and means governed by said totalizer to cause said shaft

to go through two complete cycles of carry- 65 ing.

2. In a calculating machine, the combination of a source of power adapted to be intermittently connected to said machine to actuate the same, a trip to determine when 70 said source of power shall be connected to the machine, a totalizer, carrying mechanism which sometimes requires but one cycle of operation and sometimes requires two cycles, and a control for said trip acting automatically to cause a second cycle when necessary. 75

3. In a calculating machine, the combination of a general operator, a totalizer including a set of wheels, a carrying mechanism for said totalizer operated by said general operator, said carrying mechanism being adapted to act on said totalizer in a cycle extending from the lowest order of said totalizer to the highest order thereof, and means controlled by the highest wheel 80 of said totalizer to cause a repeated cycle of said general operator; thereby causing a second cycle of said carrying mechanism. 85

4. In a calculating machine, a totalizer, a rotatable shaft having a set of cams thereon 90 adapted to carry said totalizer wheels one at a time beginning with the totalizer wheel of lowest order, mechanism to actuate said totalizer wheels, mechanism to actuate said shaft subsequent to the actuation of said 95 totalizer wheels, said shaft actuating means being adapted to perform a carry through two complete cycles of the lowest to the highest totalizer wheel. 100

5. In a calculating machine, the combination of a totalizer, a plurality of wheels in 105 said totalizer, carrying mechanism connecting said wheels, actuating mechanism adapted to enter a number of more than one digit into said totalizer, said totalizer wheels being arranged so as to permit the entering of a number into a plurality of decimal orders thereof, carrying mechanism, a general operator, manually operated means for tripping said general operator, and means governed by an operation of said carrying mechanism for also tripping said general operator. 110

6. In a calculating machine, the combination of a totalizer, means to enter a number 115 into said totalizer in a plurality of decimal orders thereof, a general operator to actuate said number-entering means, means governed by an operation of entering a number in said totalizer for tripping said general 120 operator, and a second control for said general operator.

7. In a calculating machine, the combination of a general operator, a totalizer, a set 125 of wheels in said totalizer, carrying mechanism for said wheels, said carrying mechanism being operated by said general operator and also being adapted to act on said

- totalizer in a cycle extending from the lowest order of said totalizer to the highest order thereof, and means controlled by the highest wheel of said totalizer to cause a 5 repeated cycle of said general operator, thereby causing a second cycle of said carrying mechanism.
8. In a calculating machine, the combination of a source of power adapted to be connected to said machine to actuate the same through a cycle, a totalizer, keys to determine the entering of numbers into said totalizer, and means whereby the operation of the machine through a cycle to enter a number therein as determined by said keys may, if necessary, cause said source of power to operate said machine through its second cycle.
9. In a calculating machine, the combination of computing mechanism including carrying mechanism, operating mechanism, and means whereby an operation of said carrying mechanism through a cycle may, if necessary, cause an actuation of said operating mechanism through a second cycle to complete the carrying operation.
10. In a calculating machine, the combination of a totalizer capable of algebraic addition and subtraction, carrying mechanism adapted ordinarily to operate through a single cycle, and means controlled by the element of highest order to cause said carrying mechanism when necessary to operate through a second cycle.
11. In a calculating machine, the combination of calculating mechanism including register wheels and carrying mechanism, a motor for operating said calculating mechanism through a cycle, and means for causing said motor to operate said mechanism through a second cycle in case the register wheel of highest order is caused by said carrying mechanism to pass the space between 9 and 0.
12. In a calculating machine, the combination of a series of totalizer wheels, a series of carrying devices each of which is adapted to have a partial operation imparted thereto by a totalizer wheel, operating mechanism including a series of successively acting devices arranged to complete the operation of said carrying devices, one of said carrying devices being operated by the wheel of highest order and, when its motion is completed,
- acting on the wheel of lowest order, and the first of said successively operating devices being arranged to act in the denomination of lowest order, whereby the totalizer wheel of lowest order will be the first one to receive a carrying operation.
13. In a calculating machine, the combination with totalizer wheels, and carrying means capable of algebraic calculation, of means brought into action by the act of passing through zero for assuring an operation of the carrying mechanism through a second cycle.
14. In a calculating machine, the combination with totalizer wheels, and delayed acting carrying mechanism operating on the wheels successively, of means brought into action by the act of passing through zero for imparting a second cycle of operation to said carrying mechanism.
15. In a calculating machine, the combination of totalizer wheels, a set of carrying pinions each adapted to have an initial operation imparted thereto by a totalizer wheel, a series of devices acting successively on said pinions to complete the operation thereof, said pinions including one operated by the wheel of highest order and mounted on a shaft and said shaft having also another pinion acting on the wheel of lowest order.
16. In a calculating machine, the combination of totalizer wheels, a set of carrying pinions each adapted to have an initial operation imparted thereto by a totalizer wheel, a series of devices acting successively on said pinions to complete the operation thereof, said pinions including one operated by the wheel of highest order and mounted on a shaft and said shaft having also another pinion acting on the wheel of lowest order, and means controlled by said shaft for assuring a second cycle of operation of said devices.
17. In a calculating machine, the combination of totalizer wheels, carrying mechanism, operating mechanism, and means controlled by the highest totalizer wheel to automatically cause a second operation of said operating mechanism and carrying mechanism.

In witness whereof I have hereunto signed my name this 11th day of September, 1916.

ARTHUR F. POOLE.
